UNITED STATES PATENT OFFICE

CHARLES HUENLICH, OF BLOOMFIELD, NEW JERSEY, ASSIGNOR TO THOMAS A. EDISON,
INCORPORATED, OF WEST ORANGE, NEW JERSEY, A CORPORATION OF NEW JERSEY

RECORD SUPPORT FOR PHONOGRAHPS

Application filed November 28, 1931. Serial No. 577,756.

This invention relates to record supports or mandrels, and more particularly to improved record supports or mandrels for phonographs.

Ordinarily commercial phonographs employ cylindrical records or tablets which are adapted to be supported by rotary supports or mandrels and to be firmly or loosely mounted by reason of the expansion or contraction of certain parts or members of the supports. For illustration, the present invention is shown applied to a phonograph record support of the type disclosed in U. S. Patent No. 1,213,197, to Newman H. Holland, granted January 23, 1917. However, this improvement may be applied equally as well to all types of supports wherein the installation or removal of the sound record is accomplished by contracting a record engaging portion or portions of said supports. Record supports of this type are known in the art as "collapsible mandrels" and have been developed mainly to avoid difficulties arising from the fact that wax records are susceptible to expansion and contraction under temperature variations. Collapsible mandrels such as disclosed in the Holland patent referred to, avoid such difficulties by providing a support in which the record engaging means are yieldingly mounted for movement toward and away from the axis of the support. However, the construction shown in said patent is open to the objection that manipulation of the end knob is necessary each time a record is applied to the support and is again necessary each time a record is removed.

The principal object of my invention is to provide, in a support of this general character, a construction in which after the removal of a record therefrom, the necessity of a second manipulation of the mandrel when a new record is placed thereon, is eliminated.

Another object of my invention is to provide a construction which insures the positioning of a record cylinder at a predeter-

mined point longitudinally of the support or mandrel whenever the cylinder is operatively held by the latter.

Still another object of my invention is to provide a collapsible mandrel of the character described which after removal of a record cylinder therefrom, will be in a collapsed condition ready to receive another cylinder without the necessity of further manipulation.

A further object of the invention is to provide a construction wherein the application of a record cylinder to the support or mandrel will first effect the collapsing of the latter, facilitating such application, and will thereafter effect the expansion of the mandrel, preferably upon the cylinder reaching a given position lengthwise on the mandrel.

A still further object of my invention is to prevent the application of a record to the support unless the latter is collapsed.

Other objects and features of my invention will appear more clearly from the following description taken in connection with the accompanying drawing and the appended claims.

In the drawing:

Fig. 1 is a front elevation, partly broken away, of a phonograph structure provided with one form of a record support or mandrel embodying my invention;

Fig. 2 is a longitudinal sectional view of the record support shown in Fig. 1, with the parts in the positions they occupy when a record has been mounted thereon;

Fig. 3 is a sectional view of the support taken on line 3—3 of Fig. 2;

Fig. 4 is a sectional view taken on line 4—4 of Fig. 2;

Fig. 5 is a detailed elevation view;

Fig. 6 is an elevational view partly in section showing a modified form of record support in accordance with my invention;

Fig. 7 is a sectional view on line 7—7 of Fig. 6;

Fig. 8 is a fragmentary sectional view of a part of the structure shown in Fig. 6; and

Fig. 9 is a perspective view of the double arm latching member employed in the support shown in Fig. 6.

The phonograph to which my invention is shown applied in Fig. 1, is of well known construction and comprises a bed plate 1 provided with standards 2 and 3. Supported 10 at one end in the standard 3 is a stationary tube or sleeve 4 secured rigidly in position by a set screw or equivalent means 5. The driving shaft 6 of the phonograph is mounted to extend through the tube 4, the left hand 15 end of said shaft (Fig. 2) being rotatable within a bearing 7 in the corresponding end of the tube or sleeve 4. A knurled nut 8 secured to the right hand end of the shaft 6, as shown in Fig. 2, engages the corresponding 20 end of a tube 17 and cooperates with the end portion 18, engaging the end of the sleeve 4, to prevent the shaft 6 from shifting longitudinally with reference to the tube 4. Power is transmitted to the driving shaft of 25 the phonograph by means of a belt (not shown) encircling a pulley 10 rotatable on the shaft 11, which latter is secured in the standard 2 by a set screw or equivalent means. Any means may be provided to prevent later- 30 al movement of the pulley 10, such as a set screw 10' fitting in an annular groove (not shown) in the shaft 11. The shaft 11 is axially in line with shaft 6, to which it is adapted to be connected by a clutch 15, one 35 member of which is slidable back and forth upon the enlarged portion 9 of the driving shaft 6. Gear 16 is secured to the said shaft portion 9; and from this gear, by connections (not shown) the feed screw of the phonograph is driven in the usual manner.

The record support or mandrel proper has a tubular shaft 17 which is rotatably mounted upon the sleeve 4 by means of bearings 13 and 14 and is provided with a reduced right 45 hand end portion 18 to cooperate with the sleeve 4 and the nut 8 to prevent longitudinal movement of the shaft. The reduced portion 18 is slotted to receive a pin 18' carried by the drive shaft 6, and thus the shaft 17 is 50 caused to rotate with the shaft 6.

Reference characters 19 and 20 represent a pair of adjacent flanges or discs mounted on the shaft 17 adjacent its left hand end, the disc 19 being loose on the shaft and the disc 55 20 being secured thereto by a set screw 21 passing through the collar 22, preferably formed integrally with the latter disc. The discs 19 and 20 are preferably of the same diameter and are resiliently connected, preferably 60 by means of a spiral spring 23 having bent ends respectively engaging in openings provided therefor in the respective flanges or discs. The face of disc 19 adjacent disc 20 is preferably provided with a depression or 65 circular recess 26 within which the spring 23

is located, whereby the discs may be maintained in close proximity to each other, as shown in Fig. 2. Disc 20 is provided with a number of similar and equally spaced slots 70

27, and disc 19 with a corresponding number of slots 28 of the same size as slots 27 and 75 respectively cooperating therewith in the manner about to be set forth. The outer walls of all the slots 27 and 28 are located at the same distance from the axis of the shaft 78

6, slots 27 being arranged radially of the axis of the support, while the slots 28 in disc 19 are preferably arranged at acute and equal angles to the slots 27, as shown in Fig. 80

3. This arrangement of the discs 19 and 20 forms no part of the present invention, and for more detailed description thereof reference may be had to Patent No. 1,213,197, referred to above. Reference character 29 represents rods or members which extend longitudinally of the shaft 17 and are adapted 85

to engage the bore of a phonograph record cylinder A. Rods 29 are preferably cylindrical and correspond in number to the number of slots 27 or 28, these rods being 90

formed with slightly reduced cylindrical inner end portions 30 respectively engaging the cooperating pairs of slots 27 and 28 in discs 19 and 20. The reduced portions 95

30 are slightly less in diameter than the width of slots 27 and 28, whereby they may readily move therein during the manipulation of the support. Into the inner end of each rod 29 is threaded a screw 31, the head of which 100

cooperates with the shoulder 32 formed on the rod by its reduced portion 30, to maintain disc 20 closely adjacent to disc 19 and at the same time to prevent substantial longitudinal movement of the rod 29 with respect to shaft 17. The reduced portion 30 of each rod 105

29 is preferably slightly greater in length than the combined thickness of discs 19 and 20 so as to permit movement of the outer end of the rod toward and away from the axis of shaft 6 about the inner end thereof. Spring 110

23 is so arranged that, whenever the reduced end portions 30 of rods 29 are seated in the cooperating pairs of slots 27 and 28, it will be under tension and consequently tend to turn or rotate disc 19 on shaft 17 and with 115

respect to disc 10 in the direction of the arrow in Fig. 3, and thus, by the cooperation of the walls of the respective pairs of relatively angularly disposed slots 27 and 28 with such reduced portions 30, to maintain the inner ends of rods 29 in their outermost positions in engagement with the outer end walls of the slots 27 and 28, as shown in Fig. 3. The portion of disc 20 which extends outwardly of the rods 29 serves as an abutment against 120

which the inner end of record cylinder A should be pushed when applied to the support. Another flange or disc 33 is slidably mounted on the shaft 17 adjacent the outer end thereof and is provided with similar and 125

130

equally spaced openings 34 disposed at equal distances from the axis of shaft 6 and corresponding in number to the slots 27 and 28. The inner walls of opening 34 are located 5 slightly nearer to the axis of shaft 6 than those of slots 27. The openings 34 extend through slightly more than a semi-circle so that the rods 29 are retained against disengagement laterally from disc 33 and at the 10 same time extend slightly beyond the edges of the disc so as to be adapted to engage the bore of the sound record. By reason of the location of the openings 34 nearer the axis of shaft 6 than the slots 27, the support 15 formed by the rods 29 has a slight taper toward the outer end thereof. The disc 33 is provided on the inner end of a tubular member 35, which is slidably mounted on the shaft 17, this member being preferably provided 20 with an operating head or knob 36. A coil spring 37 is disposed within the member 35 between the head 36 and the nut 8, and tends to hold said member and thereby the disc 33 in its outermost position. The disc 25 33 when in this position maintains rods 29 in firm engagement with the bore of a record A mounted thereon, as shown in Fig. 2. A screw 38 (see Fig. 1) is secured to the shaft 17 and its head cooperates with a longitudinal slot 39 in member 35 to hold the disc or flange 33 with its openings 34 in axial alignment with the slots 27 in the disc or flange 19. This screw also serves by its engagement with the ends of said slot, to limit 30 35 the axial movement of the member 35 and thereby of flange or disc 33.

The relative location of the slots 27 in flange 19 and the openings 34 in the flange 40 or disc 33, is such that when the inner ends of rods 29 are substantially in engagement with the outer walls of slots 27, and the flange 33 is in its outermost position, the taper of the support formed by rods 29 substantially 45 conforms to the taper of the bore of the record A, as shown in Figs. 1 and 2. Moreover, the support is so designed that when the parts are in the positions just described, the bore of a record placed thereon will tightly engage the 50 rods 29 when the inner end of the record is still a slight distance from the disc 19. It is evident that an inward pressure on record A sufficient to cause movement of the inner end of any of the rods 29 towards the axis of 55 the support will, by reason of the engagement of the rods with the respective pairs of relatively inclined slots 27 and 28, cause rotation of disc 19 with respect to disc 20 in a direction opposite the arrow shown in Fig. 3 and 60 thereby cause a like movement of the rest of the rods 29. By reason of the relative arrangement of the radial slots 27 in disc 10, and the inclined slots 28 in disc 19, rods 29 will be caused to move simultaneously and 65 uniformly toward or away from the axis of

the support, according to the direction of rotation of disc 19.

The parts thus far described are substantially similar to those disclosed in the patent to Holland mentioned above. From the foregoing it will be readily understood that when it is desired to remove a record from the support, the knob 36 must be pressed or moved toward the left in order to release the gripping pressure exerted by the rods 29 on the bore of the record, this pressure arising from the action of spring urged flange 33 upon the inclined or tapered portions 40 of rods 29. Similarly, when a record A is to be mounted 70 on the support it becomes necessary to again 75 press knob 36 inwardly to collapse rods 29 so as to permit the record to be moved to a position on the support where it engages disc 20. As hereinbefore stated, it is the prime 80 object of my invention to eliminate this latter manipulation, and one means for effecting this result in the particular form of supports or mandrel above described, will now be 85 explained.

Secured to the knob 36 by a screw 41 is a 90 long sleeve 42 extending towards the discs 19 and 20 and having a collar 43 at its extremity, this collar being provided with an inclined face 44 and a vertical side 45 adapted to cooperate with a latching member 46 which 95 is pivoted at 47 on a lug 48 formed integrally with the disc 20. From Figs. 2 and 3 it will be noted that the member 46 pivots at both sides of the lug 48 upon a pin 49 and that the mid-section of the lug is cut out to receive a coil spring 50 for urging the latch in a clockwise direction and its right hand or latching end towards the shaft 17 for engagement with the collar 43 of sleeve 42. The latching member 46 is provided at the left 100 of its pivot with an upwardly extending end portion 51 which normally is in a position located in the path of a record being applied to the support. The disc 20 is provided with a notch 52 adapted to receive the extension 51 105 when a record is moved to its full operative position on the support. When no record is 110 on the support, the parts normally occupy the positions shown in Fig. 1, the tubular member 35 then being held adjacent the inner limit 115 of its axial movement and the rods 29 collapsed and ready to receive a record without pressing the member 35 inwardly any further.

When the parts are in the positions just described it will be seen that accidental tripping of the latching member 46 would release sleeve 42 and member 35 and thereby result in the expansion of the supporting rods 29. This would be objectionable as a record 120 is ordinarily moved to position over the support with the rods 29 collapsed and any attempt to push a record to full operative position on the support with the rods expanded, 125 would be almost sure to result in the record 120

being broken or seriously damaged. To eliminate the possibility of an operator forcing a record upon the support when the parts are not properly positioned to receive the same, the following precautionary construction has been provided: Radially and pivotally mounted on the member 35 by means of the lugs 55 are a number of obstructing pawls or fingers 56, which are respectively aligned with the ends of the rods 29 and are adapted to cooperate therewith, as seen in Fig. 4. Each of the supporting lugs 55 is slotted at mid-section and a coil spring 57 is disposed in the slot and about the pivot pin of the corresponding pawl or finger 56, which spring has its ends bearing against the lug and the pawl and constantly tends to urge the pawl towards the corresponding rod 29 and away from the member 35. If the latching member 46 is accidentally displaced and disengaged from the collar 43, the member 35 will be moved to the right to the limit of its outward movement, determined by the slot 39 and screw 38, and in this position of member 35 the right hand ends of the rods 29 will be at such a distance from the pawls 56 as to permit the latter to assume the positions shown in Fig. 5. The pawls 56 are then substantially at right angles to the member 35, further movement about their pivots in a clockwise direction being prevented by the engagement of shoulders 59 thereof with the lugs 55. As the diameter of the circle defined by the outer ends of the pawls 56 is then greater than the bore of the cylindrical records, the application of a record on the support is prevented until the member 35 is again moved inwardly and retained in that position by the latching member 46. Possible damage to records is thus eliminated.

Figs. 6, 7, 8 and 9 show a modified form of my invention applied to the same type of record support as described above. The description of the parts employed in this modification will now follow.

Referring to Fig. 6, it will be noted that a slidable tubular member 60 is connected to the flange 33 and is provided at its left hand end with an enlarged portion 61 adapted to cooperate with another slidable hollow cylindrical member 62. A coil spring 63 constantly tends to hold member 62 in engagement with the enlarged end portion 61 of member 60, as shown in Fig. 6. The member 62 is provided with a flange 64 suitably notched at 65 to receive the rods 29 and has radially extending portions or fingers 66 adapted to be engaged by a record on the support. The notches 65 prevent rotation of the flange 64 and thereby member 62 in respect to the shaft 17. The disc 20, in this instance, is provided with three notches 67 for the reception of fingers 66 so that the flange 64 may be moved close to said disc with said fingers substantially flush with the latter, thus providing for

movement of a record on the support to its full operative position. Pivots mounted at diametrically opposite points on the member 62 is a double-armed latch 68 which has a semi-circular connecting band 69 and is normally urged upwardly by a spring 70. The end portion 61 of tubular member 60 is provided with diametrically disposed vertically extending slots 71 adapted to register with the ends of the latch 68. When the parts assume the positions shown in Fig. 6, the ends of latch 68 will engage, through the openings 71, the head portion 61 and thereby hold these parts together. Extending longitudinally of the support and within the member 62 is a pin 72 which is secured to the disc 20 and is adapted to engage at times with the band 69, this engagement being made possible by an opening 73 in the right hand wall of the member 62. Alignment of the member 61 in respect to the member 62 is maintained by means of the set screw 38 and the slot 39 of the tubular member 35 previously described. The structure just described and embodied in this form of my invention is operated as follows: The support with the parts positioned as shown in Fig. 6, is ready for the reception of a cylinder. It will be noted that the member 35 is in its outermost position and that the rods 29 are fully expanded. Upon pushing a cylinder or record on the support it will engage the fingers 66 of flange 64 before it has been advanced far enough along the support to be gripped by the tapered structure formed by the rods 29. Further pressure on the record will then cause the member 62 to be moved toward the left and to carry with it, by reason of its latched connection therewith, the member 60 and the operating member 35. Such movement of member 35 effects the contraction of rods 29, and consequently the cylinder may be pushed up all the way to the left end of the support and against the disc 20 without any direct movement or manipulation of the member 35. However, approximately at the end of this movement of the record the pin 72 will pass through the opening 73 in the member 62 and will engage and trip latch 68 thereby releasing the tubular member 60 from its connection with member 62. Under the influence of the heavy spring 37, the operating member 35 will then be moved to the right and effect the expansion of rods 29 to hold the record firmly on the support.

When it is desired to remove the record, the member 35 is pressed or moved toward the left, causing the tubular member 60 to slide along the member 17. This operation contracts the rods 29 sufficiently so that the record will be fairly loose thereon whereupon the spring 63, if the left hand end of the enlarged portion 61 of member 60 is not already in engagement with the opposed annular surface of member 62, will move the lat-

ter slightly to the right until such engagement is effected. Such movement of member 62 will, of course, also be imparted to the record A by the fingers 66. The hook or 5 latching ends of latch 68 will then have passed through slots 71 and be slightly to the right of the shoulder of member 60 in which such slots are provided. Upon now removing pressure from member 35, spring 37 will

10 act to move member 60 to the right and member 62 will under the action of spring 63, follow member 60 in such movement until the latch disengages pin 72. Thereupon spring 70 will at once move latch 68 to its 15 operative position to thereby connect members 60 and 62. The members 60 and 62 will then continue to move to the right under the action of spring 37 until member 60 reaches the limit of its outermost position as determined by the engagement of the screw 38, 20 secured to the shaft 17, with the left hand end of slot 39 formed in the member 35 (see Fig. 1). The parts will then be in the positions shown in Fig. 6 with the rods 29 fully 25 expanded. The movement of member 62 to the right under the action of springs 63 and 37, as described, insures that the record A, in the operation of removing the same, will be maintained loose on the support during 30 the expansion of rods 29 as member 35 is moved to the right by spring 37. The record may now be readily slipped off the support and the latter then be ready to receive another record.

35 It is understood that my invention is susceptible of embodiment in many other forms than the illustrative constructions shown and described, without departure from the scope of the appended claims.

40 What I claim is:

1. In a record support, expandible and contractable record engaging members which are substantially immovable lengthwise of the support, means operable to effect the contraction of said record engaging members to permit the removal of a record from the support, and means adapted upon such contraction of said record engaging members to condition the support for the reception of 45 another record without further manipulation than the moving of the latter record on the support to its operating position.

2. In apparatus of the class described, an expandible and contractable record support, 50 a device adapted to lock the support in contracted condition, and means for effecting the operation of said device upon removal of a record from the support.

3. In a record support, expandible and contractable record engaging members which are substantially immovable lengthwise of the support, means for expanding said members, and means for effecting the operation of said expanding means by the application of a record to the support.

4. In a record support, expandible and contractable record engaging members which are substantially immovable lengthwise of the support, means for expanding said members, and means for effecting the operation of said expanding means upon a record reaching a predetermined point on said support when applied thereto. 70

5. In a record support, expandible and contractable record engaging members which are substantially immovable lengthwise of the support, said members being normally in expanded condition, means for contracting said members and means for effecting the operation of said contracting means by the 75 application of a record to the support. 80

6. In a record support, expandible and contractable record engaging members which are substantially immovable lengthwise of the support, means for contracting and expanding said record engaging members, and means for effecting the operation of said first means to first contract and thereafter expand said record engaging members when a record is moved over the support in a given direction. 85 90

7. In a record support, expandible and contractable record engaging members which are substantially immovable lengthwise of the support, means movable relatively to said members to and from position for preventing the application of a record to the support, and means for effecting the movement of said preventing means to operative 95 100 position when said record engaging members are expanded.

8. In a device of the class described, an expandible record support, means comprising a spring for expanding said support, said support being contractable to facilitate the removal of a record therefrom, and means operable by said spring to apply a force to the record tending to remove the same from the support. 105

9. In a device of the class described, an expandible record support, means comprising a spring for expanding said support, said support being contractable to facilitate the removal of a record therefrom, and means operable by said spring for moving the record along said support. 110 115

10. In a device of the class described, an expandible and contractable record support, means for contracting said support to loosen a record mounted thereon, and means rendered operative upon the actuation of said contracting means to move the record relatively to the support to a position in which it will be loose with respect to the support even though the latter be thereafter expanded. 120 125

11. In a record support, contractable and expandible record holding members biased to expanded position, manually operable 130 means for contracting said members to re-

- lease a record for removal thereof, retaining means for holding the members in contracted position, and means for automatically releasing said retaining means when a record is positioned on said members. 19. In a support for cylindrical records, record holding means expandible to and contractible from operative position, means for expanding and contracting said holding means, including a device for storing energy 70 and in which energy is stored only when said holding means are contracted, and means for releasably locking said holding means contracted.
12. In a record support, contractable and expandible record engaging members biased to expanded position for holding a record thereon, means for holding said members in contracted position during and after the removal of a record from the support, and means for releasing the contracted members automatically by the positioning of a record on the support. This specification signed this 25th day of 75 November, 1931.
13. In a record support, contractable and expandible record holding members which are substantially immovable lengthwise of the support, means for contracting said members to release and thereby permit removal 80 of a record therefrom, and means rendered operable to expand said members by the application of a record to the support.
14. In a record support, movable members for holding a record, means for controlling the movement of said members, and a device adapted to maintain said means inoperative when no record is operatively positioned on the support. 85
15. In a record support, record holding members movable to and from operative position, means for controlling the position of said members, an operating member for said means, and means operable by a record when moved on said members to control the operating member. 90
16. In combination, a record support having contractable and expandible record engaging members, and means associated with said support and operative to indicate the position of said members. 95
17. In a support for cylindrical records, record holding means movable to and from operative position, a device capable of storing energy and operable by energy stored therein to move said holding means to operative position, a member movable to effect movement of the record holding means to inoperative position, said member when so moved effecting the storing of energy in said device, and means for releasably locking said member in a position wherein energy is stored in said device. 100
18. In a support for cylindrical records, record holding means movable to and from operative position, a device capable of storing energy and operable by energy stored therein to move said holding means to operative position, and a member movable to effect movement of the record holding means to inoperative position, said member when so moved effecting the storing of energy in said device, said device being rendered operable to move said holding means to operative position by a record in the application thereof to the support. 105
19. In a support for cylindrical records, record holding means expandible to and contractible from operative position, means for expanding and contracting said holding means, including a device for storing energy 110 and in which energy is stored only when said holding means are contracted, and means for releasably locking said holding means contracted.
20. In a record support, contractable and expandible record holding members which are substantially immovable lengthwise of the support, means for contracting said members to release and thereby permit removal of a record therefrom, and means rendered operable to expand said members by the application of a record to the support. 115
21. In a record support, record holding members movable to and from operative position, means for controlling the position of said members, an operating member for said means, and means operable by a record when moved on said members to control the operating member. 120
22. In combination, a record support having contractable and expandible record engaging members, and means associated with said support and operative to indicate the position of said members. 125
23. In a support for cylindrical records, record holding means movable to and from operative position, a device capable of storing energy and operable by energy stored therein to move said holding means to operative position, and a member movable to effect movement of the record holding means to inoperative position, said member when so moved effecting the storing of energy in said device, said device being rendered operable to move said holding means to operative position by a record in the application thereof to the support. 130
